UNITED STATES PATENT OFFICE.

CHARLES H. MILLER, OF MILWAUKEE, WISCONSIN, ASSIGNOR TO THE CUTLER-HAMMER MANUFACTURING COMPANY, OF MILWAUKEE, WISCONSIN, A CORPORATION OF WISCONSIN.

SELF-STARTER FOR ELECTRIC MOTORS.

No. 921,430.

Specification of Letters Patent.

Patented May 11, 1909.

Application filed October 24, 1904. Serial No. 229,872.

To all whom it may concern:

Be it known that I, CHARLES H. MILLER, a citizen of the United States, residing at Milwaukee, in the county of Milwaukee and State of Wisconsin, have invented new and useful Improvements in Self-Starters for Electric Motors, of which the following is a full, clear, concise, and exact description, reference being had to the accompanying 10 drawing, forming a part of this specification.

My invention relates to improvements in self starters for electric motors, and has for its object to provide means whereby the motor may be controlled by variations in pressure in a compression tank.

It is particularly adapted for use in connection with the self starters for electric motors, comprising broadly a rheostat for a motor having the movable element thereof 20 operated through the medium of a solenoid, and the present object of my invention is to provide means for automatically closing the circuit through said solenoid for operating said movable element when the pressure in a 25 compression tank falls below a certain definite amount and for opening a circuit through said solenoid when the pressure in the compression tank rises to a predetermined point.

I have shown a diagrammatic view of my 30 invention in the accompanying drawing forming a part of this specification.

In the preferred embodiment of my invention I provide a pressure regulator, 1, having contact points 2, and 3, formed thereon and a 35 solenoid 4, which is adapted to operate the switch 5 and close the circuit between the two contacts 6 and 7. Magnetic blow-outs 5^a are electrically connected to the contacts 6 and 7. The circuit controlled by this solenoid switch contains therein the solenoid winding 8, which operates the movable element 9 of the resistance 10, said resistance being subdivided into sections and connected with the series of contacts 11, over which 40 said movable element 9 is adapted to sweep. A conductor 9^a connects the hub of the contact arm 9 with the second of the contacts 11, whereby in event contact between the arm and the contacts should be defective, the arm 45 current will still find a path through the conductor 9^a and the resistance 10. The resistance 10 is connected in the circuit of the motor 12, having the field winding 13.

In operation, when the needle point 14 of 50 the pressure regulator 1, which is adapted to

be moved over the face thereof by the rise and fall of the pressure in a compression tank 14^a is moved to the left by the lowering of the pressure it makes contact with the contact point 2, and circuit is closed from the line 15, over the wire 16, to the binding block 17, mounted upon the same base as the solenoid winding 4, conductor 18 to the contact 2, of the pressure regulator, over the needle point 14, by conductor 19, to the 60 binding block 20, through the winding of the solenoid 4, by conductor 21, through the resistance 22, binding block 23, conductor 24, to the binding block 25, mounted upon the support for the self starter of the motor and 65 from thence by conductor 26 over the movable element 9 by conductor 27, binding block 28, conductor 28^a, to the opposite side of the line 29. The resistance 42 will thereby be short circuited and sufficient current 70 will be admitted to the solenoid winding 4 to operate its core and raise the contact 5, thereby closing the circuit through the two contacts 6 and 7 and from thence to the motor. The motor circuit may be traced as 75 follows: line 15, conductor 16, binding post 17, contact 6, movable contact 5, contact 7, conductors 30 and 30^a, armature 12, conductor 35, binding post 35^a, conductor 35^b, resistance 10, movable element 9, and back 80 to the opposite side 29 of the line, the field circuit being traced from conductor 30^a, through field winding 13, conductor 36, binding block 37, conductor 38, binding block 28, and back to the opposite side 29 of 85 the line. When the motor circuit is closed, circuit is also closed through the solenoid 8, which circuit may be traced as follows: conductor 30, binding post 30^b, winding of the solenoid 8, conductor 31, across the 90 switch 32, conductor 33, conductor 27, binding block 28, and back to the opposite side 29 of the line. The winding of the solenoid 8 being thus energized, it operates the movable element 9, to move the same over the 95 contacts 11, thereby removing the resistance 10 in the motor circuit, and causes the motor to gradually build up in speed. When the arm 9 has reached its final position, the switch 32 is moved out of contact with the 100 contact point 39 and the resistance 40 is inserted in the circuit of the winding of the solenoid 8. After the movable element 9 has moved from the first contact 34, a 105 resistance 41 is inserted in the circuit of the 110

winding of the solenoid 4, thereby preventing the same from overheating.

As the motor operating the pump 12^a gradually increases the pressure in the 5 compression tank, the needle 14 moves to the right away from the contact 2 and the current through the winding 4 then passes through the resistance 42, to the winding 4, instead of taking the shorter path through 10 the contact 2 and the needle of the pressure regulator. Sufficient current however passes through the solenoid to maintain the contact 5 in a closed position and the motor continues to run until the pressure increases 15 sufficiently to cause the needle to make contact with the contact 3, which is connected by conductor 43, with the conductor 21, thereby short-circuiting the same, so that the contact bridge 5 opens the circuit between 20 the contacts 6 and 7, thereby opening the motor circuit and stopping the same. Under these conditions current may be traced from the binding post 17, through the resistance 42 to the conductor 19 across the 25 needle 14 to contact 3, and thence by conductor 43, through the resistance 22, to the binding post 23, from thence by conductor 24 to the binding post 25, on the self starter, conductor 26, contact 34 of the motor resistance, through the resistance 41, hub of the 30 movable element 9, conductor 27, binding post 28, conductor 28^a and opposite side of the main 29. The resistance 22 is arranged in series with the contact 3 of the pressure 35 switch to prevent arcing between the contacts 2 and 3 of the pressure switch when said contacts are set close together, as they usually are in pressure gages.

Having described my invention what I 40 claim as new and desire to secure by Letters Patent is:

1. The combination with a motor, and a resistance therefor, of a magnetically operated switch controlling the circuit through 45 said motor and said resistance, means for reducing the current traversing the magnet of said switch, a device responsive to fluid pressure, which in one position renders said means inoperative and in another position 50 renders said magnet inoperative, and a resistance adapted to be included in circuit with said magnet, when the starting resistance, is removed from circuit, and adapted to be removed from circuit when the starting 55 resistance is in circuit.

2. The combination with a motor and a resistance therefor, of a magnetically operated switch controlling the circuit through said motor and resistance, a resistance arranged 60 in the circuit of the operating magnet for said switch, a shunt extending around said resistance, a fluid pressure operated switch arm moving between stops and adapted when in contact with one stop to close said 65 shunt and when in engagement with the

other stop to close a shunt circuit around said magnet, and a second resistance adapted to be included in circuit with said magnet when the starting resistance, or a part thereof, is removed from circuit, and be cut out 70 when the said resistance is in circuit.

3. The combination with a motor, of a controller therefor, an electromagnetic winding for automatically actuating said controller, a magnetically operated switch for controlling the circuit through said motor and said winding, means for reducing the current traversing the operating magnet of said switch, and a fluid pressure device, which is adapted in one position to render 80 said means ineffective, and in another position to render said magnet inoperative.

4. The combination with a motor, of a controller therefor, an electromagnetic winding for actuating said controller, a magnetically operated switch for controlling the circuit through said motor, and said winding, a resistance arranged in the circuit of the controlling magnet of said switch, a shunt extending around said switch, and a fluid pressure operating switch arm, which is adapted when in one position to close said shunt, and in another position to close a shunt circuit around said magnet.

5. The combination with a motor, of a controller therefor, an electromagnetic winding for actuating said controller, a magnetically operated switch for controlling the circuit through said motor and said winding, means for reducing the current traversing 100 the operating magnet of said switch, and means for rendering said reducing means ineffective under predetermined conditions, said means under other predetermined conditions rendering said magnet inoperative.

6. The combination with a motor, of a controller therefor, an electromagnetic winding for actuating said controller, a magnetically operated switch for controlling the circuit through said motor and said winding, 110 means for reducing the current traversing the operating magnet of said switch, and a switch which in one position renders said means ineffective, and in another position renders said magnet inoperative.

7. The combination with a motor, of a resistance therefor, a movable element for controlling said resistance, an electromagnet for operating said movable element to remove said resistance from the motor circuit, and an electromagnetic switch for controlling the circuit through said electromagnet, said electromagnetic switch being operated to make said circuit by automatic means closing a shunt circuit around a resistance in 120 series with said electromagnetic switch and operated to break said circuit by automatic means closing a shunt circuit around said electromagnetic switch.

8. The combination with an electromag- 130

netic switch provided with a resistance in series with the winding thereof, of automatic means for short circuiting said resistance on the occurrence of predetermined conditions to energize said electromagnetic switch to close a circuit through an electromagnet associated with a controller, and means connected with said controller for increasing a resistance in series with said controller-
10 electromagnet.

9. The combination with a motor, of a controller therefor, an actuating electromagnet connected with said controller, an electromagnetic switch for controlling the continuity of the motor and controller-
15 electromagnet circuits, a resistance in series with said electromagnetic switch, and means for automatically short circuiting said resistance on the occurrence of one kind of pre-
20 determined conditions and for short circuiting the electromagnetic switch on the occurrence of another kind of predetermined conditions.

10. The combination with a motor, of a controller therefor, an actuating electromagnet connected with said controller, an electromagnetic switch for controlling the continuity of the motor and controller-
25 electromagnet circuits, a resistance in series with said electromagnetic switch, means for automatically short circuiting said resistance on the occurrence of one kind of predetermined conditions and for short circuiting the electromagnetic switch on the occurrence of
30 another kind of predetermined conditions, and means connected with said controller for increasing the resistance of the electromagnetic switch circuit.

11. The combination with a motor, of a controller therefor, an actuating electromagnet connected with said controller, an electromagnetic switch for controlling the continuity of the motor and controller-
35 electromagnet circuits, a resistance in series with said electromagnetic switch, means for automatically short circuiting said resistance on the occurrence of one kind of predetermined conditions and for short circuiting the electromagnetic switch on the occurrence of
40 another kind of predetermined conditions, means connected with said controller for increasing the resistance of the electromagnetic switch circuit, and means associated with said controller for increasing the resistance of the controller electromagnetic circuit.

12. In a controller for electric motors, the combination with an electromagnetically operated rheostat, of an electromagnetically operated motor switch, an automatically operated controlling switch, circuit connections whereby said controlling switch, in one position, causes the magnet of said motor switch to respond and close said motor switch and causes the rheostat to operate to start the

motor and in another position causes the magnet of said motor to be deenergized, and a maintaining circuit for energizing said magnet when said controlling switch is in an intermediate position.

13. In a motor controller, the combination with an electromagnetically operated rheostat, of an electromagnetically operated motor switch, a pressure operated switch, circuit connections whereby said pressure switch, in one position, causes the magnet of said motor switch to respond to close said motor switch and causes the rheostat to operate to start the motor and in another position causes said magnet to be deenergized, and a maintaining circuit for energizing said magnet when said pressure switch is in an intermediate position.

14. In a motor controller, the combination with an electromagnetically operated rheostat, of an electromagnetically operated motor switch, a pressure operated switch, circuit connections whereby said pressure switch, in one position, causes the magnet of said motor switch to respond and close said motor switch and causes the rheostat to operate to start the motor and in another position short-circuits said magnet, and a maintaining circuit for energizing said magnet when said pressure switch is in an intermediate position.

15. The combination with an electromagnetically operated switch, of an automatically operated switch movable between stops, said last mentioned switch when in engagement with one of said stops being adapted to cause the energization of the operating winding of the first mentioned switch and when in engagement with the other of said stops to cause the deenergization of said winding, and a resistance connected in circuit with one of said stops to prevent arcing between said stops.

16. The combination with an electromagnetically operated switch, of an automatically operated switch movable between stops, said last mentioned switch, when in engagement with one of said stops, being adapted to cause the energization of the operating winding of the first mentioned switch and when in engagement with the other of said stops to close a shunt-circuit around said winding, and a resistance connected in circuit with said last mentioned stop and said winding to prevent arcing between said stops.

17. The combination with an electromagnetically operated switch, of a resistance connected in circuit with the operating winding of said switch for rendering said winding ineffective to close said switch, and a pressure operated switch movable between fixed stops, said pressure switch, when in engagement with one of said stops, being adapted to close a shunt-circuit around said resistance

and when in engagement with the other of said stops to cause the deenergization of said winding, and a resistance connected in circuit with one of said stops and said winding to prevent arcing between said stops.

18. The combination with an electromagnetically operated switch, of a resistance connected in circuit with the operating winding of said switch for rendering said winding 10 effective to close said switch, a pressure operated switch movable between fixed stops, said pressure switch, when in engagement with one of said stops, being adapted to close

a shunt-circuit around said resistance and when in engagement with the other of said stops to close a shunt-circuit around said winding, and a resistance connected in circuit with said last mentioned stop and said winding to prevent arcing between said stops.

In witness whereof, I have hereunto subscribed my name in the presence of two witnesses.

CHARLES H. MILLER.
